BAG-FRAME FASTENER

William H. Zachman, Woodhaven, N. Y., assignor
to United-Carr Company, Inc., Brooklyn, N. Y.,
a corporation of New York

Application September 26, 1934, Serial No. 745,533

5 Claims. (Cl. 292—228)

My invention aims to provide improvements in fasteners for bag-frames of the type having channel members of U-shaped cross-section.

In the drawing, which illustrates a preferred form of my invention:

Figure 1 is a top view of the fastener showing sections of the frame in the closed position;

Fig. 2 is a section on the line 2—2 of Fig. 1;

Fig. 3 is a rear view of the latch member and its supporting plate;

Fig. 4 is a bottom view of the latch member as shown in Fig. 3;

Fig. 5 is a perspective view of part of a bag frame in the open position, showing the coacting parts of my improved fastener; and

Fig. 6 is a perspective view of the fastener and supporting plate showing the construction of the spring and the hinged assembly of the parts.

My improved fastener is adapted particularly, though not exclusively, for use with a frame of the type illustrated. That is, a frame made from material of U-shaped cross-section and having upwardly, rather than downwardly, extending side-walls. The specific form of my invention, as illustrated, comprises a supporting plate 1, a latch member 2 pivotally mounted thereon, and a spring 3 for actuating the member 2. The supporting plate 1 is secured to the frame member 4. A cooperating catch piece 6 is secured to the second frame member 5, all as shown in Fig. 2. The supporting plate 1 is preferably made from rigid sheet metal and is provided with a pair of attaching lugs 7 extending from one edge. These lugs 7 have bifurcated ends which are spread apart after the lugs are inserted in properly sized apertures in the frame, thus making a secure assembly. At the other side of the plate 1 is a relatively wide flat projection 8 having a pair of rectangular apertures 9. I have located these apertures 9 so that they lie on a line parallel to that side of the plate from which extend the lugs 7 and far enough from that side so that they will be located above the side wall of the frame member 4 (Fig. 3) when the plate is secured to it.

The latch member 2 is made from sheet metal and is of box-like construction, having a rear wall 10, and side walls 11. The flat top is curved slightly upwards near the front end, as best shown in Fig. 2. Instead of an upright wall at the front side of the latch, I have provided a relatively long, rearwardly disposed lip 12, which extends back toward the rear wall 10 and is spaced from the main part of the latch. This lip 12 is curved approximately the same as the

main plate (Fig. 2) so that when the two parts of the frame are pushed together the lip will act as a cam with the catch-piece 6, causing the latch to ride up over the catch until the frame is completely closed and the rear edge of the lip 12 snaps down over the catch as in Fig. 2.

From the edge of the rear wall 10 extend a pair of lugs 13 which serve to attach the latch member to the supporting plate 1. When assembled, the supporting plate 1 extends up into the latch 10 member inside the rear wall 10 and almost to the top of the latch member. The projection 8 is approximately as wide as the inside dimension of the latch member, so that the rear end of the latch member is well supported. The lugs 13 are passed through the apertures 9 and bent upwardly, thereby forming hinges, as is best shown in Fig. 6. By the construction of these hinges and the relation between the rear wall 10 and the projection 8, the motion of the latch member is limited to a rather short arc, which is very desirable inasmuch as the latch member can never fall below the point where it will be acted upon by the catch 6 when the frame is being closed.

In order to make the latch member snap down over the catch-piece, I have assembled in the latch member the wire spring 3. This spring extends from outside the supporting plate 1, against which it bears (Figs. 4 and 6), up into the latch member 2, across the latch member near the plate 1, and the other end bears downwardly on the lip 12. This spring is held in place solely by its own tension on the component parts of the latch and acts as a torsion spring to press the latch member downwardly so that it will always engage the catch 6 except when purposely lifted.

From the above description and drawing, it will be seen that the plate 1, the latch member 2, and the spring 3 are really a unit. For this reason I prefer to assemble them before attaching the plate to the frame in the manner described above.

The catch-piece 6 (Figs. 2 and 5) is formed from sheet metal and has lugs 15 of the same type as those on the plate 1 and used in the same manner. The head of the catch 6 is formed by bending the material double and making the free end flare outwardly as in Fig. 2. This flared portion acts as a cam to insure a tight closure of the frame jaws.

From the above description it is obvious that my invention provides a very simple and easily manufactured bag-frame fastener. Its operation is simplicity itself,—to close the bag it is merely necessary to squeeze the jaws of the frame together, causing the latch member to be lifted

against the action of the spring by the catch-piece and to pivot upwards on its hinges 13. When the jaws are fully closed the latch member snaps down over the catch 6, which engages 5 the rear edge of the lip 12. The latch member is held in that position by the spring 3 until the bag is to be opened; then it is only necessary to lift the latch member at its front edge so that it will pivot high enough to disengage the catch 6.

10 While I have illustrated and described a preferred form of my invention, I do not wish to be limited by such description since the scope of my invention is best defined by the following claims.

I claim:—

- 15 1. A fastener for bag-frames and the like comprising a supporting plate having an aperture adjacent to one side thereof, means on said plate for attaching it to a frame member, a latch member comprising a plate having rear and end walls, a rearwardly disposed lip extending from the front edge of the plate between said end walls, a pair of ears extending from said rear wall through the apertures in said supporting plate whereby the latch member is hinged to the supporting plate and a wire spring bearing on said lip and the outside of said supporting plate to hold the latch member in its normal position.
- 20 2. A fastener for bag-frames and the like comprising, in combination, a rigid supporting plate having a lateral projection at one side thereof and a plurality of attaching lugs at the other side thereof, a latch member formed from sheet metal and having a plate portion and rear and end walls, a rearwardly disposed lip extending from the front edge of said latch member in spaced relationship to the plate portion thereof and terminating in a line spaced from said rear wall, the lateral projection of said support extending into said latch member closely adjacent 35 to the inner side of said rear wall and presenting a pair of apertures located beneath the edge of said rear wall, a pair of bendable ears extending from said rear wall directly through said apertures and bent upwardly on the inner side of said supporting plate whereby said latch member is hinged to said supporting plate, and a wire spring bearing on said lip and the outside of said supporting plate to hold the latch member in its normal position.
- 30 4. A fastener for bag-frames and the like comprising a latch member of substantially rectangular construction having rear and end walls and a rearwardly disposed lip extending from the front edge thereof and adapted to engage a catch-piece, a supporting plate having a portion extending into said latch member closely adjacent the rear wall thereof, means on said rear wall
- 45

whereby said latch member is hinged to said supporting plate and movable in a limited arc, a wire spring bearing on said rearwardly disposed lip adjacent to one end of the wall of the latch member and extending along the plate portion of the latch member adjacent to the rear wall thereof, and the other end of said spring bearing on the outside of said supporting plate whereby said latch member and said supporting plate are normally held at substantially right angles to one another.

4. A fastener for bag-frames including a plate adapted to be secured to a frame member, said plate having a projecting portion presenting a plurality of apertures therethrough, a latch member formed from sheet metal and having a substantially perpendicular flange along one end, said flange lying outside said projecting portion, a plurality of bendable ears extending from said flange through the apertures in said projecting portion whereby said latch member is hinged to said plate at one end, catch-engaging means provided as a part of said latch member for engagement with a cooperating catch member and a spring assembled with said parts to engage said latch member and said plate for normally pressing said latch member into catch-engaging position.

5. A fastener for bag-frames including a plate adapted to be secured to a frame member, said plate having a portion provided with a plurality of apertures therethrough, a latch member formed from sheet metal and having a substantially perpendicular flange along one end, a plurality of bendable ears extending from said flange through said apertures in said plate whereby said latch member is hinged to said plate at one end, a lip extending in spaced relation to the under side of said latch member from the front edge thereof toward the hinged end and forming catch-engaging means and a wire spring having one end bearing on that side of said plate opposite to the side at which the latch member extends, and said spring having a portion extending into the latch member inside said flange and adjacent to one end of the projection on said plate, said spring having its mid-portion bent at a right angle to said plate-engaging end portion and extending along the under side of said latch member adjacent to the edge of the apertured projection on said plate and the other end of said spring being bent at a right angle to the mid-portion and bearing downwardly upon said lip whereby said latch member is normally pressed into catch-engaging position when the fastener is attached to a frame.

WILLIAM H. ZACHMAN.
